(57) **CLAIM**

We claim the ornamental design for a model vehicle axle carrier, as shown and described.

DESCRIPTION

FIG. 1 is a top, front, left side perspective view of a model vehicle shock tower showing our new design;

FIG. 2 is a left side view thereof;

FIG. 3 is a right side view thereof;

FIG. 4 is a front side elevation view thereof;

FIG. 5 is a rear side elevation view thereof;

FIG. 6 is a top plan view thereof;

FIG. 7 is a bottom plan view thereof; and,

FIG. 8 is a bottom, rear, right side perspective view of the model vehicle shock tower.

In the drawings, the broken lines illustrate portions of the model vehicle axle carrier that form no part of the claimed design.
